UNITED STATES PATENT OFFICE.

MICHAEL ZWIEBEL, OF PAPILLION, NEBRASKA.

DESIGN FOR A CIRCULAR SAW.

SPECIFICATION forming part of Design No. 32,820, dated June 12, 1900.

Application filed March 13, 1900. Serial No. 8,553. Term of patent 7 years.

To all whom it may concern:

Be it known that I, MICHAEL ZWIEBEL, a citizen of the United States, residing at Papillion, in the county of Sarpy and State of Nebraska, have invented and produced a new and original Design for Circular Saws; and I do hereby declare the following to be a full, clear, and exact description of the invention, such as will enable others skilled in the art 10 to which it appertains to make and use the same.

In the drawings, Figure 1 is a side view of the saw. Fig. 2 is a side view of some of the saw-teeth, drawn to a larger scale. Fig. 3 is 15 a plan view of the teeth. Fig. 4 is a cross-section taken on the line $x-x$ in Fig. 2.

As shown in the drawings, the leading or material feature of the design consists of a circular disk D, having series of teeth A and 20 B. The teeth B have parallel sides and are arranged in pairs, the teeth comprising each

pair being bent to the right and to the left in opposite directions. The teeth A are straight teeth and have inclined side portions b extending from their middle portions to their 25 tips, which terminate in sharp central points b', arranged centrally of the points of the bent teeth B. All the teeth A and B are of equal height and are arranged upon the same circular arc. All the teeth A and B also have 30 substantially radial faces c and inclined flanks d, and the faces and flanks are all arranged at the same angle to each other.

What I claim is—

The design for a circular saw, as herein 35 shown and described.

In testimony whereof I affix my signature in presence of two witnesses.

MICHAEL ZWIEBEL.
